US00D909764S

(12) **United States Design Patent** (10) Patent No.: **US D909,764 S**
(45) Date of Patent: **** Feb. 9, 2021**

(54) **THERMOSET SURFACE MATERIAL WITH ORNAMENTATION**

(71) Applicant: **DUPONT SAFETY & CONSTRUCTION, INC.**, Wilmington, DE (US)

(72) Inventor: **Massimo Fucci**, Milan (IT)

(73) Assignee: **DUPONT SAFETY & CONSTRUCTION, INC.**, Wilmington, DE (US)

(**) Term: **15 Years**

(21) Appl. No.: **29/708,095**

(22) Filed: **Oct. 3, 2019**

(51) LOC (13) Cl. **05-06**

(52) U.S. Cl.

USPC **D5/56; D5/43**

Primary Examiner — Karen S Acker

CLAIM

The ornamental design for a thermoset surface material with ornamentation, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a top plan view of a thermoset surface material with ornamentation, showing my new design.

1 Claim, 1 Drawing Sheet
